United States Patent Office

Des. 196,715
Patented Oct. 29, 1963

196,715

HOUSE

Donald J. Scholz, Toledo, Ohio, assignor to Scholz Homes
Inc., Toledo, Ohio, a corporation of Ohio

Filed June 22, 1962, Ser. No. 70,654

Term of patent 14 years

(Cl. D13—1)

FIG. 1 is a front perspective view of a house embodying my new design;

FIG. 2 is a front elevational view of the house;

FIG. 3 is a left side elevational view in reduced scale;

FIG. 4 is a right side elevational view in reduced scale;

FIG. 5 is a rear elevational view in reduced scale;

FIG. 6 is a top plan view in still further reduced scale; and

FIG. 7 is an alternative front elevational view of the house.

For convenience of illustration, only parts of the brick side surfaces have been shown in the several views of the

drawings. It is to be understood that these surfaces continue throughout the plane areas shown.

The modified design of FIG. 7 is identical to the design of FIGS. 1 through 6 except that the garage door is eliminated from the left side of the house and is located at the front side thereof.

I claim:

The ornamental design for a house, as shown and described.
